PROCESS OF NITRATING METHANE

George K. Landon, Wilmington, Del., assignor
to Hercules Powder Company, Wilmington,
Del., a corporation of Delaware

Application January 11, 1938, Serial No. 184,386

7 Claims. (Cl. 260—644)

This invention relates to the nitration of methane for formation of nitromethane.

Heretofore it has been known to nitrate paraffin hydrocarbons having from 3 to 8 carbon atoms, e. g. according to the process disclosed in United States Letters Patent No. 1,967,667. No attempt was made to use hydrocarbons having more than 8 carbon atoms, nor to use the simple hydrocarbons, such as methane or ethane, which have only primary carbon atoms. Later, it was disclosed in United States Letters Patent No. 2,071,122 that, by altering the conditions of nitration, ethane could be nitrated.

I have found that methane may be nitrated, by the use of aqueous nitric acid, very simply and at good yields, by the use of the process in accordance with this invention.

Specifically, my method of nitration of methane includes passing the reactants through the heated reaction zone at high velocity and at pressures from atmospheric pressure to about 800 lbs. gauge pressure, vaporization of the aqueous nitric acid almost instantaneously as it is fed in, the use of apparatus in which the product comes into contact with no ferrous metal (instead of the stainless steel heretofore employed), and the injection of cooling gases into the reaction mixture to control the temperatures and increase yields.

Methane is far less reactive than ethane or the higher homologs, and nitromethane is comparatively unstable at the high temperatures necessary for its formation; hence it is essential that it be removed from the hot zone very rapidly.

In nitration of ethane, the best yield is obtained at a reaction temperature of about 352° C. and a contact time of the reactants at this temperature of about 9.7 seconds. Attempts to use the above conditions in nitrating methane were unsuccessful.

The method, heretofore used, of vaporizing nitric acid by bubbling the hydrocarbon through a body of nitric acid held at constant temperature makes it difficult, if not impossible, to feed to the reaction zone anything except a constant boiling mixture. High pressures are impossible, because vaporization is prevented unless the nitric acid be raised to a temperature dangerous from the explosive point of view. My improved method avoids these disadvantages.

Furthermore, I have found that, in the nitration of methane, the presence of stainless steel causes decomposition of the nitromethane formed, resulting in extremely low yields. My

improved process avoids this decomposition by the use of apparatus in which the product comes into contact with no ferrous metal, for example, apparatus of glass, glass-lined, gold, platinum, or gold-lined or platinum-lined apparatus, and produces nitromethane at satisfactory yields.

As a specific example of the carrying out of my process I pass methane, preheated to a temperature of, for example, about 500 to about 700° C., into a small chamber, through which passes a small diameter tube carrying aqueous nitric acid under pressure, said tube being preferably constructed of platinum or gold, or lined and coated therewith, said nitric acid thus being converted into vapor and escaping from the extremity of said tube into the heated methane and mixing therewith.

Said mixture of nitric acid vapor and methane may be maintained in the proportion of from about 2 to 40 mols CH_4 per mol of HNO_3 , preferably 1 mol HNO_3 to 10 mols of CH_4 . This mixture is then passed, at a velocity represented by a contact time with reaction vessel, of about 0.005 to 1.0 second, depending upon the temperature of the reaction zone, into and through a reaction zone or apparatus, preferably comprised of a tube of "Pyrex" glass or any suitable metal lined with gold or platinum, maintained at a temperature within the range of about 375° C. to about 550° C., preferably about 440° C. to 460° C., thence to any suitable condenser and receiver capable of withstanding pressure.

As a specific example of the process in accordance with my invention, using a salt bath temperature of 460° C., a molar ratio of

1 HNO_3 :17 CH_4

a contact time of 0.10 second and a pressure of 100 lbs. gauge, I obtained nitromethane at a yield of 45.8%, based upon the HNO_3 consumed.

Further to explain the process in accordance with my invention, reference is made to the accompanying drawing in which 1 represents a tube through which is passed methane, heated, for example, to about 500-700° C. by a heater (not shown), passing into receiver 2, which surrounds and heats platinum pipe 3, through which passes dilute nitric acid, e. g. of 35-40% concentration. The methane passes then into "Pyrex" glass coiled tube 4, and mixes with the vapors of nitric acid escaping from the end of the tube 3, the mixture then passing through the remainder of coil 4 immersed in a bath of molten salt mixture comprising equal parts of KNO_3 and NaNO_3 , maintained at a temperature of, for example,

440-460° C., thence through condenser 5 and to receiver 6, where the liquid products, mainly nitromethane and nitric acid, collect and may be drawn off via valve 7 and pipe 8, while the gas products, mainly unreacted methane and nitrogen oxides, pass off via valve and pipe 10 for recovery or waste.

The bath of molten salt, 11, contained in any suitable vessel, 12, is maintained at the desired temperature by direct heating, submerged electrical heating units, or in any suitable manner.

Preferably, I maintain a pressure upon the reactants of about 100 lbs. to about 800 lbs.

What I claim and desire to protect by Letters Patent is:

1. The process of nitrating methane, which includes producing contact between methane and nitric acid in a non-ferrous vessel at reaction temperature, both reactants being in the vapor phase, the time of contact in the reaction zone between the reactants being from about 0.005 to about 1.0 second and the reactants under superatmospheric pressure, rapidly removing the reaction mixture from the zone of reaction and cooling it.

2. The process of nitrating methane, which includes producing contact between methane and nitric acid at a temperature between about 375° C. and about 550° C., in a non-ferrous vessel, both reactants being in the vapor phase, the time of contact in the reaction zone between the reactants being from about 0.005 to about 1.0 second and the reactants under a pressure within the range of atmospheric to about 800 pounds, rapidly removing the reaction mixture from the zone of reaction and cooling it.

3. The process of nitrating methane, which includes producing contact between methane and nitric acid at a temperature of about 450° C. in a non-ferrous vessel, both reactants being in the vapor phase, the time of contact in the reaction zone between the reactants being from about

0.005 to about 1.0 second and the reactants being under a pressure within the range of atmospheric to about 800 pounds, rapidly removing the reaction mixture from the zone of reaction and cooling it.

4. The process of nitrating methane, which includes producing contact between methane and nitric acid at a temperature of about 460° C. in a non-ferrous vessel, both reactants being in the vapor phase, the time of contact in the reaction zone between the reactants being about 0.10 second and the reactants being under pressure of about 100 pounds, rapidly removing the reaction mixture from the zone of reaction and cooling it.

5. The process of nitrating methane, which includes producing contact between methane and nitric acid in a non-ferrous vessel, in the molar ratio of 1 nitric acid to 17 of methane, at a temperature of about 460° C., a contact time between the reactants of about 0.10 second, the reactants being in the vapor phase and under a pressure of about 100 lbs., rapidly removing the reaction mixture from the zone of reaction and cooling it.

6. The process of nitrating methane which includes producing contact between methane and nitric acid while in the vapor phase in a vessel having a non-ferrous inner surface and at reaction temperature for a period of time within the range of about 0.005 second to about 1.0 second, rapidly removing the reaction mixture from the reaction zone, and cooling it.

7. The process of nitrating methane which includes producing contact between methane and nitric acid in the vapor phase in a vessel having a non-ferrous inner surface and at a temperature within the range of about 375° C. to about 550° C. for a period of time within the range of about 0.005 second to about 1.0 second, rapidly removing the reaction mixture from the reaction zone and cooling it.

GEORGE K. LANDON.
